CHEMICAL PROCESS

Charles E. Hemminger, Westfield, N. J., assignor
to Standard Oil Development Company, a corporation of Delaware

Application December 1, 1939, Serial No. 307,015

4 Claims. (Cl. 196—52)

The present invention relates to improvements in the conversion of relatively high boiling hydrocarbons to fractions boiling within the gasoline range. More particularly, the present invention relates to vapor phase catalytic cracking of relatively high boiling hydrocarbons under conditions such that when the fresh feed is vaporized, at least a portion of the catalyst is present in the oil during the transition from the liquid to the vapor phase.

One object of the present invention is to crack hydrocarbons in the presence of a powdered catalyst suspended in the hydrocarbon vapors under conditions such that the tar or coke which is formed during this type of operation, which tends to deposit on the inner walls of tubes or other surfaces contacting the hydrocarbons during the reaction, is removed from the said walls of tubes or surfaces or to prevent such deposition in the first instance, by virtue of the scrubbing or abrasive action of the catalyst.

Another object of the present invention is to vaporize the entire fresh feed in the presence of catalyst thus avoiding the usual flash towers.

To the accomplishment of the foregoing and similar ends, I provide a process which is fully disclosed in the present specification and claims, reference being also had to the accompanying drawing.

The drawing is a diagrammatic illustration in partial vertical section showing suitable apparatus in which my present invention may be carried into effect.

Referring in detail to the drawing, a distillate gas oil obtained either from crude petroleum oil or from a cracked stock, is introduced into the system through line 1. This gas oil may be the usual material understood by the term, e. g. a product having a mid-boiling point of about 700° F. A catalyst such as an acid treated clay or a silica gel, silica-alumina compositions or gels or the like is removed from some suitable reservoir 2, by any feeding means such as a star conveyor 3 and then forced through line 4 and line 5 into injector 6 where it admixes with the gas oil. The amount of catalyst introduced from reservoir 2 to line 1 may be from 10 to 100% of the total amount eventually introduced into the oil. Good results are obtained by introducing from about 10% to 25% of the total catalyst at this point. The mixture of oil and catalyst is then discharged into line 7 and thence into a coil 8 in furnace 8 where the oil passes from the liquid to the vapor phase in the presence of the catalyst. The vaporized oil, having an outlet temperature

of about 900° F. and containing the catalyst, is then discharged into line 10. At this point, the remainder, if any, of the catalyst is introduced into the vaporized oil through valved line 11 into mixing device or injector 12. The vaporized oil containing the catalyst suspended therein is then discharged into line 14, thence into drum 15 where the main reaction takes place. The reaction products are withdrawn through line 16 and then discharged into a cyclone separator 17 where the major portion of the catalyst is removed from the vapors. The separator 17 may be of conventional design and furthermore, two or more of these separators may be employed in series. The vapors are withdrawn from the separator through line 18 and discharged into fractionating column 19, from which an overhead product containing gasoline and normally gaseous hydrocarbons are withdrawn through line 20, discharged into a condenser 21, thence into a receiving drum 22 from which the normally gaseous hydrocarbons are withdrawn through line 23 and gasoline and the greater portion of the unconverted gas oil are recovered through line 24.

The bottoms from tower 19 are withdrawn through line 25 and returned to line 16 as indicated. The bottoms from tower 19 will contain the remainder of the catalyst which was not removed by the cyclone separator.

The cyclone separator 17 may be superimposed on baffled tower 30 and the catalyst liberated in separator 17 may fall through the tower against steam admitted through line 31. The steam serves to purge the catalyst of volatile hydrocarbons. Nitrogen, CO₂, flue gas or any heat stable gas not containing substantial quantities of free oxygen may also be used for this purpose. From tower 30, the catalyst is discharged through star feeder 34 into line 35 and thence into injector 36. Meanwhile a heated regeneration gas is fed from line 37 into injector 36 where it disperses the catalyst causing entrainment or suspension of the latter in the gas and this mixture is withdrawn through line 38, and forced into a coil 39 in heat exchanger 40 where tarry deposits or coke on the catalyst are burned off. Good results are obtained in the regeneration using a regeneration gas containing 2% to 10% oxygen, the remainder being N₂, steam, CO₂, flue gas or the like. This regeneration gas may have an inlet temperature of from about 500 to 800° F. and sufficient inlet pressure to provide an outlet or back pressure in discharge line 41 of say 1 to 4 atmospheres on the pressure gauge. Some of the

heat developed in coil 39 may be withdrawn by forcing water, admitted through line 43 into heat exchanger 40, through the bank of pipes forming coil 39, but externally of the several pipes. The steam formed may be withdrawn through line 44. Molten salt may also be used in place of water for temperature control. The catalyst suspended in the gaseous combustion products is fed through line 41 to cyclone separator 45 where the catalyst is separated from the gas and then passes through baffled tower 46 to screw conveyor 47. Steam or other purging gas may be introduced through line 48 to flow countercurrently against the down coming catalyst to purge the latter. Screw conveyor 47 therefore receives hot catalyst which it feeds to hopper 2. The gaseous products of combustion are rejected through line 49.

Numerous modifications of the foregoing process may be made without departing from the spirit of the present invention. For instance, the gas oil distillate may be heated in coil 8 to a temperature from about 300 to 600° F., at pressures from the range of 10 to 50 pounds or from temperatures as high as 800° F. where the pressures are greater than 100 pounds per square inch gauge. The temperature of the material leaving coil 8 may be as high as 1000° F. The catalyst which is in powdered form may have a size varying in the range from about 100 to 400 mesh. The temperatures prevailing in the cracking vessel 15 may vary from 750 to 1000° F. The pressures in this element may vary from atmospheric to 500 pounds per square inch gauge. Steam or other vapors may be added to the feed to coil 8 to assist in the vaporization of the oil therein. The total catalyst to oil ratio may vary from $\frac{1}{2}$ to 20 parts catalyst per 1 part oil by weight. The catalyst may be hotter than the oil

so that the residual heat from regeneration may be used to heat the oil or its vapors. The vapors may be resident in the cracking vessel 15 for a time within the range of from about 5 to 25 seconds. Furthermore, the drum 15 may be merely an insulated drum or it may be a heated drum or coil.

Numerous modifications of my invention may be made by those skilled in this art and it is my intention to claim the invention as broadly as the language of the appended claims will permit.

What I claim is:

1. In a process for the catalytic cracking of hydrocarbon oil in the presence of a finely divided regenerable catalyst which remains solid under the cracking and regenerating conditions, the improvements which comprise adding to the oil while it is in liquid condition a portion of the total quantity of cracking catalyst which is to be used, vaporizing the oil in the presence of said portion of the catalyst, then adding to the vaporized oil the remainder of the catalyst prior to any substantial cracking of said oil vapors and thereafter maintaining said oil in contact with said catalyst for a period sufficient to obtain substantial cracking thereof.
2. Process according to claim 1 in which a minor proportion of the total quantity of cracking catalyst to be used is added to the oil while it is in liquid condition.
3. Process according to claim 1 in which from 10 to 25% of the total quantity of catalyst is added to the oil while the latter is in liquid condition.
4. Process according to claim 1 in which hot freshly regenerated catalyst is added to the oil both before and after vaporization.

CHARLES E. HEMMINGER.
